THREAD-CONTROLLING MECHANISM FOR
SEWING MACHINES

Frederick F. Zeier, Fairfield, Conn., assignor to
The Singer Manufacturing Company, Elizabeth, N. J., a corporation of New Jersey

Application April 10, 1941, Serial No. 387,809

5 Claims. (Cl. 112—246)

This invention relates to chain-stitch sewing machines, and more particularly to a thread-controlling mechanism for a thread-carrying looper having loop-seizing and -shedding movements.

In the production of stitched articles it is desirable when sewing fabrics having inherent extensibility to employ a seam having a corresponding amount of elasticity, so that stretching of the fabric will not result in a fracture of the thread or threads comprising the stitched seam. Also, when sewing fabrics having substantially no inherent extensibility and when a very fine flat seam is necessary, such for example as in the manufacture of men's shirts, it is desirable to form a seam having comparatively little elasticity. It is common knowledge in the sewing machine art that a two-thread chain-stitch seam will possess inherent elasticity if it is formed so that the needle-thread-loops remain relatively long and when concatenated with the looper-thread are folded back and lie against the looper-side of the fabric. Likewise, it is well known in the art that a two-thread chain-stitch seam possesses relatively little elasticity when the needle-thread-loops extend beyond the looper-side of the fabric only sufficiently far to properly anchor the looper-thread at the bends thereof.

In prior sewing machines the conversion from the elastic seam to the inelastic seam or vice versa was not always possible and in the machines where the conversion was possible the same could be accomplished only after the thread-tensions were readjusted and the customary thread take-up and pull-off elements reset or retimed relative to the movements of the looper. To accomplish this readjustment and retiming a trial-and-error method had to be resorted to in order to obtain the desired result. This is time-consuming and therefore objectionable.

It is the primary object of the present invention to provide a conveniently adjustable thread-controlling mechanism which in one position of adjustment functions in the production of an elastic chain-stitch seam and, in another position of adjustment, functions in the production of a relatively inelastic chain-stitch seam.

This objective is attained by providing an adjustable thread-controller which in one position of adjustment maintains control of the looper-thread throughout substantially the entire stitch-forming cycle, and in another position of adjustment maintains control of the looper-thread during a portion only of the stitch-forming cycle.

The above and other objects will in part be

obvious and will in part be hereinafter more fully disclosed.

In the drawings which show by way of illustration one embodiment of the invention:

5 Fig. 1 is a front elevational view, partly in section, of a sewing machine embodying the present invention.

10 Fig. 2 is an enlarged top plan view of the forward portion of the machine-bed with the cloth-plate removed to expose the mechanisms within the bed.

Fig. 3 represents a vertical sectional view taken substantially along the line 3—3, Fig. 1.

15 Fig. 4 represents a vertical sectional view taken substantially along the line 4—4, Fig. 3, showing the thread-controller in its position to assist in the production of an elastic seam, the full lines showing the thread-controller arm at the lower end of its stroke and the dotted lines showing 20 the thread-controller arm at the upper end of its stroke.

Fig. 5 represents a vertical sectional view taken 25 substantially longitudinally of the seam, showing the seam produced when the thread-controller is adjusted as illustrated in Fig. 4.

Fig. 6 is a view similar to Fig. 4, but with the thread-controller in its position to assist in the production of an inelastic seam, the full lines showing the thread-controller arm at the lower 30 end of its stroke and the dotted lines showing the thread-controller arm at the upper end or ineffective position of its stroke.

Fig. 7 represents a view similar to Fig. 5, showing the seam produced when the thread-controller is adjusted as illustrated in Fig. 6.

Referring more in detail to the drawings, the invention is illustrated as applied to the chain-stitch sewing machine forming the subject of my copending application Serial No. 316,297, filed 40 Jan. 30, 1940. That portion of the sewing machine shown comprises a bed 1 from one end of which rises a standard 2 of an overhanging bracket-arm terminating in a head 3. The bed 1 is preferably substantially rectangular in plan view and includes front and rear vertical walls 4 and 5 connected together by two transverse partitions 6 and 7. Journaled for rotation in a suitable bearing 8 provided in the transverse partition 7 is a main-shaft 9 carrying at its forward end a crank 10 (Fig. 2) connected through suitable mechanism to a looper-carrier 11 mounted for oscillation upon a fulcrum shaft 12. Supported in the looper-carrier 11 is a pair of thread-carrying loops 13 adapted to be oscillated in a vertical plane substantially parallel

with the line of feed. Threaded through each of the loopers is a looper-thread T_L , the complete path of travel of which will be fully described hereinafter.

Cooperating with the loopers 13 is a pair of endwise reciprocating needles 14 (Fig. 1) fixed at their upper ends in a needle-clamp 15 carried at the lower end of a needle-bar 16 sustained by the machine-head 3 . Threaded through each of the needles 14 is a needle-thread T_N .

The thread-controlling mechanism for the looper-threads T_L , best illustrated in Figs. 2 and 3, preferably comprises a stationary depending U-shaped member 17 formed in each limb with a pair of thread-eyes or guides 18 , one of the limbs being vertically slotted at its upper end, as at 19 , to receive a fastening screw 20 threaded into a supporting stud 21 fixed by the set-screw 22 in the wall 4 of the bed 1 . Extending through a clearance opening 23 in the wall 4 of the machine-bed and adapted to vibrate between the limbs of the U-shaped member 17 is the free end of a thread-controlling arm 24 whose inner end is secured preferably by set-screws 25 in the socketed end of an upwardly inclined lever 26 , see Fig. 3. The lever 26 is freely fulcrumed at its lower end upon a relatively short pivot-rod 27 fastened by set-screws 28 in a lug 29 integral with the wall 5 of the machine-frame. The inclined lever 26 is oscillated about the pivot-rod 27 by a pitman 30 which at its lower end is bifurcated and pivotally receives the opposite end-portions of a pin 31 secured by a set-screw 32 against end-wise movement in the lever 26 , and at its upper end embraces an actuating eccentric 33 fast upon the main-shaft 9 . As the main-shaft is rotated, the lever 26 is oscillated about the pivot-stud 27 through the pitman 30 and the thread-controlling arm 24 is vibrated between the limbs of the U-shaped member 17 in time to properly control the looper-threads T_L .

The free end of the thread-controlling arm is bent into substantially U-shape to provide two thread-engaging limbs 34 and 35 which are disposed on opposite sides of the longer limb of the stationary U-shaped member 17 . Depending preferably upon the adjustment of the thread-controlling arm 24 in the upper end of the lever 26 , one or both of the thread-engaging limbs 34 , 35 engage the looper-threads T_L passing through the thread-eyes 18 and operate to maintain the looper-threads taut during the desired portion of each stitch-forming cycle. It will be understood that the period of effectiveness of the two thread-engaging limbs 34 , 35 depends upon their position relative to the stationary thread-eyes 18 , and that by loosening the set-screws 25 in the upper end of the lever 26 the thread-controlling arm 24 can be circularly adjusted about its longitudinal axis from the position shown in Fig. 4, in which the thread-engaging limbs 34 , 35 are disposed so that a line connecting the thread-engaging surfaces of said limbs forms an angle with a line connecting said looper-thread guides, into the position shown in Fig. 6, thereby to vary its action on the looper-threads T_L .

When the two thread-engaging limbs 34 and 35 of the thread-controlling arm 24 are adjusted as shown in Fig. 4, the looper-threads T_L are maintained under control throughout a major portion of each stitch-forming cycle; the thread-engaging limbs being ineffective on the looper-threads only during the relatively short

period of time the loopers 13 are advancing to seize the needle-thread-loops cast out by the ascending needles 14 . In operation and when the thread-controlling arm 24 is at the lower end of its stroke (shown in full lines in Fig. 4), the thread-engaging limb 34 forms a bight in the looper-threads T_L between the stationary thread-eyes 18 and in so doing takes up all the slack in the looper-threads. As the machine continues to run and looper-thread is required in the formation of the stitch, the thread-engaging limbs 34 , 35 are raised from the full line position into the dotted line position (Fig. 4). During the elevation of the limbs 34 , 35 looper-thread given up by the limb 34 between the thread-eyes 18 is immediately taken up by the limb 35 . In other words, the looper-thread T_L is engaged by the spaced thread-engaging limbs 34 , 35 seriatim. This cooperation of the two thread-engaging limbs maintains the looper-threads T_L under a substantially constant strain. As a result of the tautness of the looper-threads a greater length of needle-thread T_N is drawn from the supply per stitch with the consequence that a seam is formed having a considerably greater length of needle-thread than looper-thread (see Fig. 5).

When the thread-controlling arm 24 is adjusted so that its spaced thread-engaging limbs 34 , 35 are positioned as shown in Fig. 6, i. e., the thread-engaging limb 35 is turned into a position in which it does not engage the looper-thread T_L at any time during the stitch-forming cycle and the thread-engaging limb 34 is effective to act upon the looper-threads T_L only during a portion of each stitch-forming cycle, the looper-threads are maintained under control and substantially devoid of slack only during approximately 260 degrees of rotation of the main-shaft 9 . During the remaining degrees of rotation of the main-shaft the looper-threads are slack. When the looper-threads are subjected to this type of control the relative lengths of needle-thread T_N and looper-thread T_L are such as to result in the production of a relatively inelastic stitch, such as illustrated in Fig. 7.

It will be understood that a thread-controller constructed in accordance with the present invention is desirable for the reason that it provides means conveniently and quickly adjustable, whereby a two-thread chain-stitch sewing machine may be adjusted to effect the production of an elastic stitch or an inelastic stitch. Moreover, a thread-controller is produced which is simple in construction and susceptible of high speed operation without causing breakage of the sewing threads.

It is obvious that the invention, as defined in the appended claims, is not limited to the details of construction and arrangement of parts as shown.

Having set forth the nature of the invention what I claim herein is:—

1. In combination with a threaded reciprocating needle and a complementary thread-carrying looper, a thread-controlling mechanism including spaced thread-guides through which the looper-thread passes, a vibratory arm provided with laterally spaced thread-engaging limbs positioned to straddle at least one of said thread-guides, an oscillating lever pivotally supported at one end and provided at its other end with a socket adapted to receive said vibratory arm, a rotary shaft, means operatively connecting said

oscillating lever to said rotary shaft, and means for connecting said vibratory arm in the socket of said oscillating lever for circular adjustment about the longitudinal axis of said arm so that in one position of adjustment both of said thread-engaging limbs are effective on the looper-thread and operate to proportion the looper-thread and the needle-thread to produce an elastic stitch and in another position of adjustment only one of the thread-engaging limbs is effective on the looper-thread and operates to proportion the looper-thread and the needle-thread to produce an inelastic stitch.

2. In combination with a threaded reciprocating needle and a complementary thread-carrying chain-stitch looper, a thread-controlling mechanism including spaced thread-guides through which the looper-thread passes, means permitting adjustment of the level of said thread-guides, a vibratory arm provided with laterally spaced thread-engaging limbs positioned to straddle at least one of said thread-guides, a rotary shaft, an upwardly inclined oscillating lever pivotally supported at its lower end beneath the level of the axis of said rotary shaft, an eccentric on said rotary shaft, a pitman operatively connecting the oscillating lever to said eccentric, and means adjustably securing said vibratory arm to the upper end of said oscillating lever so that in one position of adjustment both of said thread-engaging limbs are effective on the looper-thread and operate to proportion the looper-thread and the needle-thread to produce an elastic stitch and in another position of adjustment only one of the thread-engaging limbs is effective on the looper-thread and operates to proportion the looper-thread and the needle-thread to produce an inelastic stitch.

3. In a sewing machine, the combination with a frame having a bed formed with a clearance opening therein, a threaded reciprocating needle and a thread-carrying looper, of a thread-controlling mechanism including spaced thread-guides adjustably mounted on said bed, a substantially horizontal vibratory arm extending through said clearance opening and terminating at its exposed end in laterally spaced thread-engaging limbs positioned to cooperate with said

thread-guides, a rotary shaft journaled in said bed, an upwardly inclined oscillating lever pivotally supported at its lower end beneath the level of the axis of said rotary shaft, means including a pitman connected to said oscillating lever for actuation by said rotary shaft, and means securing said vibratory arm to said oscillating lever for circular adjustment about the longitudinal axis of said arm so that in one position of adjustment both of said thread-engaging limbs are effective on the looper-thread and operate to proportion the looper-thread and the needle-thread to produce an elastic stitch and in another position of adjustment only one of the thread-engaging limbs is effective on the looper-thread and operates to proportion the looper-thread and the needle-thread to produce an inelastic stitch.

4. A thread-controlling mechanism for two-thread chain-stitch sewing machines comprising spaced looper-thread guides, and a vibratory thread-engaging member movable transversely of a line connecting said guides, said thread-engaging member including spaced thread-engaging arms one of which works on the looper-thread in the field between said thread-guides and the other of which works on the looper-thread outside the field between said guides, the thread-engaging arms being disposed so that a line connecting the thread-engaging surfaces of said arms forms an angle with a line connecting said looper-thread guides.

5. A thread-controlling mechanism for two-thread chain-stitch sewing machines comprising spaced looper-thread guides, and a vibratory thread-engaging member movable transversely of a line connecting said guides, said thread-engaging member including spaced thread-engaging arms one of which works on the looper-thread in the field between said thread-guides and the other of which works on the looper-thread outside the field between said guides, the thread-engaging arms being disposed so that a plane containing the axes of said thread-engaging arms forms an angle with the line passing through said looper-thread guides.

FREDERICK F. ZEIER.
